UNITED STATES PATENT OFFICE.

MARTIN RASMUSSEN, OF RACINE, WISCONSIN, ASSIGNOR TO HARTMANN TRUNK COMPANY, OF RACINE, WISCONSIN, A CORPORATION OF WISCONSIN.

TRUNK LOCK.

Application filed July 7, 1923. Serial No. 650,188.

To all whom it may concern:

Be it known that I, MARTIN RASMUSSEN, a citizen of the United States, and resident of Racine, in the county of Racine and State 5 of Wisconsin, have invented new and useful Improvements in Trunk Locks, of which the following is a description, reference being had to the accompanying drawings, which are a part of this specification.

10 This invention relates to trunk locks, and has for one of its objects to provide a lock which is particularly adapted for use with wardrobe trunks.

A further object of the invention is to 15 provide a lock which is especially adapted for interlocking the wardrobe and drawer sections of a wardrobe trunk.

A still further object of the invention is to provide a lock of the character described 20 which may be semi-automatically operated by the movements of the top cover section of the trunk.

A still further object of the invention is to provide a lock of the class described which 25 is adapted to engage with a keeper carried by one of the said sections before the sections are completely closed, and to positively draw such section to its fully closed position, and to there positively lock the same.

30 A still further object of the invention is to provide a lock of the character last described in which an increased leverage is obtained as the drawing action progresses.

A still further object of the invention is 35 to provide a lock of the class described which will be simple in construction, comparatively inexpensive to manufacture and install and more efficient in operation than those which have been heretofore proposed.

40 With the above and other objects in view which will appear as the description proceeds, the invention consists in the novel details of construction and combinations of parts more fully hereinafter described and 45 particularly pointed out in the appended claims.

Referring to the accompanying drawings in which like reference characters designate like parts in all the views;

50 Figure 1 is an elevational view of a wardrobe trunk, the three sections being shown in their open positions and provided with a lock constructed in accordance with the present invention;

55 Fig. 2 is a fragmentary inside elevational

view on a larger scale, of a wardrobe section, showing a lock constructed in accordance with the present invention in place thereon;

Fig. 3 is a view similar to Fig. 2, showing 60 the lock in its closed position; and,

Fig. 4 is an edge elevational view of the lock as seen from the left of Fig. 2.

Referring more particularly to the said drawings the numeral 5 indicates the wardrobe section of a wardrobe trunk, 6, the drawer section thereof, which may be hinged to the wardrobe section in the usual well known manner, and 7, the usual top cover section also hinged to the wardrobe section, 65 and adapted to close the normally open end 8 of the said wardrobe section.

The said top cover section 7 may be provided with a hasp member 9, provided with a suitable Yale or other key lock 10, adapted to co-operate with the lock receiving member 11, carried by the upper portion of the drawer section 6, when the parts are in closed position, as will be readily 70 understood.

The said drawer section 6 is provided with an escutcheon plate 12, which has rigid therewith a keeper lug or member 13 and the wardrobe section 5 carries the lock assembly 14, suitably positioned thereon to co-operate with the said keeper member 13, as will presently appear. The said lock assembly preferably comprises a casing 15, adapted to be fitted within a recess 16, provided in the wall of the wardrobe section, 80 which casing includes a pair of transversely extending guide plates 17, fitted adjacent the edges of the said recess 16.

Slidably mounted between the said guide members 17 is a reciprocating member 18, 95 which pivotally carries a pair of keeper engaging dogs or members 19, provided on their outer ends with the keeper engaging toes 20, as will be readily understood from Figs. 2 and 3 of the drawings. The said 100 members 19 are also provided with shoulders 21, provided with inclined cam surfaces adapted to engage and co-operate with the guide members 17 to force the said keeper engaging members 19 inwardly about their pivots 22 when the slide member 18 is moved to the right, as viewed in Fig. 2, thereby causing the said keeper engaging members 19 to engage the keeper member or lug 13, as will be readily understood. 110

The said members 19 are also provided with the projections 23, adjacent their pivot members 22, which are adapted to engage and co-act with a lug 24 carried by the casing 15 to move the said members 19 to their open positions when the slide member 18 occupies the position illustrated in Fig. 2.

The slide member 18 is preferably provided with an elongated aperture 35, one end of which is provided with suitable rack teeth, adapted to be engaged by the teeth of a gear or pinion 27, which is rotatably mounted on the shaft 28 of the said casing or housing 15. One end of the said shaft 28 is squared as indicated at 29, and rigidly carries the arm 30, which is provided with an elongated slot or opening 31, which receives a pin 32, carried by the lower end of the lock operating rod 33. This said rod 33 is slidably mounted in straps 34, secured to the side wall of the wardrobe section 5, and extends upwardly substantially as shown, to terminate in a head 36, positioned to be engaged by the plate 37, carried by the top cover section 7 of the trunk.

A pair of coiled springs 40 is mounted within the casing or housing 15 and engage shoulders 41, provided upon the slide member 18 and normally tend to urge the said slide member toward the right, as viewed in Fig. 2, to the open or disengaged position of the lock.

The operation of the lock will be clear from the foregoing, but it may be briefly summarized as follows:

The parts being in the position illustrated in Fig. 1 and it is desired to close and lock the sections, the section 6 is swung upon its hinges toward the section 5 in the well known manner, until the keeper member or lug 13 passes between the spaced ends 20 of the keeper engaging members 19. The top cover section 7 being now swung downwardly to close the open top 8 of the wardrobe section 5, its plate or member 37 will engage the head 36 of the rod 33 and will force the said rod downwardly. This downward movement will be communicated through the pin and slot connection, 31 and 32, to the arm 30, shaft 28, pinion 27, and from the said pinion through the rack teeth 26 to the slotted member 18, which will be moved from its position shown in Fig. 2 to that indicated in Fig. 3.

This movement of the slide member 18, will, of course, carry with it the pivoted keeper engaging members 19, the shoulders 21 of which will co-act as cams with the guide member 17 to force the said members 19 toward each other, thereby causing their shoulders 20 to engage the keeper member 13. Further movement of the slide member 18 with the keeper engaging member 19 in such closed position will cause the keeper member 13 and the entire drawer

section 6 to be positively drawn to the fully closed positions of the sections in which position they will be securely locked, due to the fact that reverse movement of the parts may only be effected when the top cover section 7 has been lifted to permit the rod 33 to rise. It will be understood of course, that when the trunk is closed the lock 10, carried by the hasp 9 of the top cover section, will be engaged with its keeper member 11 carried by the drawer section, all three sections thus securely interlocked.

When it is desired to open the trunk the lock 10 is first unlocked by the use of a key, or in any other well known manner, and the top cover section raised to its position illustrated in Fig. 1. This will release the rod 33, whereupon the coiled springs 40 will force the slide member 18 toward the left, as viewed in Fig. 2, until the projections 23 of the keeper engaging members 19 contact with the lug 24, which contact will have the effect of spreading the keeper engaging members 19 to the positions shown in Fig. 2, thereby permitting the keeper member 13 to be withdrawn as the drawer section 6 is swung outwardly.

It will be noted that at the start of the locking operation the pin 32 of the rod 33 is at the end of the slot 31 nearest to the shaft 28, see Fig. 2. However, as the rod 33 moves downwardly the said pin moves outwardly through the said slot 31 to the end thereof farthest from the shaft 28, thereby securing an increased leverage as the locking operation progresses.

While one form of the invention has been illustrated and described it is obvious that those skilled in the art may vary the details of construction as well as the arrangement of parts without departing from the spirit of the invention, and therefore it is not wished to be limited to the above disclosure except as may be required by the accompanying claims.

What is claimed is:

1. In a trunk lock, a keeper member; a lock comprising a reciprocating member; a keeper engaging member pivotally carried by said reciprocating member; means for reciprocating said member; and means operable by the movement of a section of the trunk, for actuating said reciprocating means.

2. In a trunk lock, a keeper member; a lock comprising a reciprocating member; a keeper engaging member pivotally carried by said reciprocating member; means for reciprocating said member; and means non-rigidly connected to said reciprocating means and operable by the movement of a section of the trunk, for actuating said reciprocating means.

3. In a trunk lock, a keeper member; a lock comprising a reciprocating member; a

keeper engaging member pivotally carried by said reciprocating member; means for reciprocating said member; and means having a pin and slot connection with said reciprocating means and operable by the movement of a section of the trunk, for actuating said reciprocating means.

4. In a trunk lock, a keeper member; a lock including a pair of guides, a member reciprocably mounted between said guides, and a keeper engaging member pivotally carried by said reciprocable member; oscillating means for reciprocating said member; and means having a sliding connection with said oscillatable means for moving the latter.

5. In a trunk lock, a keeper member; a lock including a pair of guides, a member reciprocably mounted between said guides, and a keeper engaging member pivotally carried by said reciprocable member; resilient means normally urging said reciprocating and keeper engaging members to-

ward their open disengaged positions; oscillating means for reciprocating said member; and means having a sliding connection with said oscillatable means for moving the latter.

6. In a trunk lock, a keeper member; a lock including a pair of guides, a member reciprocably mounted between said guides, and a keeper engaging member pivotally carried by said reciprocable member, provided with a cam surface adapted to engage one of said guides to move said keeper engaging member to its closed engaging position; resilient means normally urging said reciprocating and keeper engaging members toward their open disengaged positions; oscillating means for reciprocating said member; and means having a sliding connection with said oscillatable means for moving the latter.

In testimony whereof, I affix my signature.

MARTIN RASMUSSEN.
